STRATOSPHERIC REPRODUCING CABINET

Filed Oct. 10, 1944

UNITED STATES PATENT OFFICE

2,477,021

STRATOSPHERIC REPRODUCING CABINET

Ronald Vingoe, Wellington, Ohio

Application October 10, 1944, Serial No. 558,061

3 Claims. (Cl. 183—114.2)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to laboratory equipment and more particularly to means for maintaining stratospheric conditions within an enclosed chamber that is adapted for being installed in laboratories and the like at ground levels.

With the advent of high altitude flying during the present war, new impetus has been imparted of necessity to the investigation of the limitations of airborne equipment that are expected to function satisfactorily when subjected to the physical conditions that are encountered there. Heretofore the study of the matter has been limited very largely to the observation and the recording of the effects upon equipment and personnel of the physical conditions encountered at high altitudes. Actual flights to extremely high altitudes for the purposes of testing, improving and perfecting the equipment to be used are in some instances necessary, but in the majority of cases have been unsatisfactory, time-consuming and wasteful of effort without commensurate returns.

For some time past it has been possible and desirable to send highly sensitive and delicate instruments into the stratosphere as well as to lesser high altitudes where the instruments are to function under physical conditions that differ widely from the laboratory conditions under which the instruments are designed to deliver their optimum performance. The principal differences in physical conditions under which it is desirable that instruments and the like be adapted to continue to deliver optimum performances are in temperature, pressure, humidity, absence of particles, and partial ionization of the air. A study of the properties of air at altitudes up to 70,000 feet indicates that further control is desirable, particularly over dewpoint, freedom from contamination, and increased ionization of the gases present. The variations in the performances of instruments at high altitude conditions appears to be particularly apparent in radio equipment and in equipment having moving or rotating parts.

The objects of the present invention include the provision of means for maintaining stratospheric conditions in a suitable enclosed laboratory cabinet or chamber wherein radio sets, equipment and the like, may be removably disposed and operated under physical conditions that substantially duplicate conditions at altitudes up to 70,000 feet.

2

With the above and other objects in view which will be apparent to those who are informed in the field of development in which the present invention belongs, an illustrative diagram and flow sheet of a preferred form of device is shown in the accompanying drawing wherein:

Fig. 1 is a flow sheet indicating the chosen or preferred manner of conditioning and maintaining air in a predetermined physical state within a suitable closed cabinet or chamber.

The cabinet that is to be used in conjunction with the herein-described method of processing air that is to provide a desired atmosphere within the cabinet, has an interior that is sealed from contact with the ambient air. The cabinet 1 is lined preferably with a material that may be kept at a maximum degree of cleanliness and freedom from contaminates, such as stainless steel or the like. The cabinet 1 preferably is well insulated and is maintained at a predetermined low temperature, as by having cooling coils or the like preferably built into its walls.

All pumps, fan motors and the like, that are used in conjunction with the cabinet, are preferably mounted outside of the cabinet and are sealed against causing any contamination of the conditioned air within the cabinet by oil vapors, dust particles or the like, from the pumps and motors used with the system.

When the chamber or cabinet 1 is mechanically clean, the radio or other apparatus to be tested is positioned therein and the leads thereto are connected with fittings within the cabinet that extend through the walls of the cabinet 1 so that the apparatus can be operated and adjusted from outside of the cabinet 1.

The system is first flushed out with air by admitting and filtering compressed air from the compressed air line 2 and released through a discharge valve 3 for a desired period of time until all of the moisture and contaminants that can be eliminated from the system by this means have been removed. A valve 4 in the compressed air line 2 and the discharge valve 3 are then closed. A vacuum line valve 5 is then opened and the system evacuated after which an ambient air line valve 6 is opened and ambient air is drawn through the system. The ambient air may be drawn through a suitable filter (not shown) before entering the ambient air line 7. The purpose of this filtering step is to remove any foreign matter present in the ambient air that might foul the predryers 11. If the ambient air is sufficiently free of foreign matter the filtering step may be omitted. The ambient air then passes through

the ambient air line 7 and the connecting line 8 to branched feeder lines 9, each provided with a gating valve 10 to individually serve either or both of a pair of refrigerating predryer tanks 11.

The refrigerating predryer tanks 11 remove excess moisture from the filtered ambient air sufficiently to prolong the life period of additional drying tanks further along in the system which serve to remove the traces of moisture that pass through the predryer tanks 11. The predryer tanks 11 are of the refrigeration type and pre-cool the ambient air together with the condensation of water therefrom. In the predryer tanks 11 the filtered ambient air is chilled until all moisture in excess of saturation at the temperature there maintained is condensed out and removed from the filtered ambient air that passes beyond the refrigerating predryer tanks 11. Suitable means, such as water bleeders 12 that are closed to the outside air by valves 13 or the like, serve to remove the condensed water that accumulates within the predryer tanks 11.

The predryer tanks 11 may be refrigerated in any desired manner, as by the use of coils, tanks, or the like, through which a desired refrigerant is caused to flow. A suitable air refrigerant means that has been found to perform satisfactorily in an experimental installation comprised a mixture of Dry Ice and acetone with which the conducted air was in direct contact. In this installation, the filtered ambient air entered the refrigerating predryers 11 through an aperture in the outer wall and the moisture in the filtered ambient air condensed and solidified upon the inner walls of the predryers 11.

Suitable discharge lines 14, that are separately gated by valves 15, converge into a filter feed line 16 that opens into an activated carbon filter 17. The activated carbon filter 17 effectually removes traces of oil vapors, organic vapors, odors and other contaminants from the filtered and refrigerated ambient air that passes through it.

The filtered and refrigerated ambient air that passes through the activated carbon filter flows into a connecting line 18 from which it enters into either or both feed lines 19, that are individually gated by valves 20, and that conduct the air to calcium sulfate towers 21 where the last traces of water vapor are removed. The calcium sulfate towers 21 are preferably charged with the specially treated form of calcium sulfate that is marketed under the trade name "Drierite." Activated alumina will produce equally desirable results if used in conjunction with compressed air.

The filtered and refrigerated ambient air that passes from the calcium sulfate towers 21 is separately gated through valves 22 to a feed line 23 that conducts it to a dewpoint humidity indicator 24. The dewpoint humidity indicator 24 is preferably of the continually visible type reading directly in dewpoint values in centigrade or Fahrenheit, and serves to indicate promptly the exhaustion of the water absorbent material in the drying towers 21. The indicator 24 preferably consists of a transparent tube packed with a suitably treated desiccant which will change color upon the absorption of moisture such as the calcium sulfate used experimentally and treated to change in color from blue violet to red upon the entrance of conducted air having an undesirably high water vapor content.

A connecting line 25 conducts the circulated air to branched feeder lines 26 that are individually gated by valves 27 to precoolers 28, so that the circulated air may be conducted to either or

both of the precoolers 28, as preferred. The precoolers 28 are each provided with a drain pipe 29 that is closed to outside air by a valve 30.

The circulated air that passes through the precoolers 28 is conducted by connecting lines 31 to a feeder line 32 that conducts it to a filter 33.

A bypass 34, closed by a valve 35, joins the connecting line 18 with the feeder line 32 for use where it is desirable that the processing of the circulated air by the calcium sulfate towers 21, indicator 24 and precoolers 28 is not necessary. A bypass 36, closed by a valve 37, connects the connecting line 25 with the feeder line 32, for use where the effect of the precoolers 28 upon the circulated air is not necessary. A bleeder 38 opening to the ambient atmosphere and closed by a valve 39 is provided in the feeder line 32 to bleed in under vacuum enough untreated atmospheric air to increase the moisture content of the circulated air to a desired value depending upon the reading of the dewpoint indicator 24.

The predryers 11, dryers 21, and the precoolers 28 are preferably installed in parallel pairs in order that longer tests may be conducted without closing down the conditioning system to recharge these elements or to blow any condensed moisture out of the precoolers and the predryers.

A conducting line 40 connects the filter 33 with a flow meter 41. The flow meter 41 is connected by a conducting line 42 with the altitude chamber 1. Suitable means, such as a bypass 43 around the flow meter 41 and equipped with a valve 44 is provided for cutting the flow meter out of the line.

The conditioned air within the altitude chamber 1 is ionized in any preferred manner, and preferably by the use of an ultraviolet source 45 within the altitude chamber 1. The ultraviolet source may be in the form of an incandescent wire, a flame, a radioactive material, a carbon arc, or the like. The degree of ionization of the air within the cabinet 1 should duplicate, as nearly as is practicable possible, that of the atmosphere at the altitude at which the equipment within the chamber is to be tested. A safety filter 46 preferably is also provided to minimize damage to the vacuum pump from carbon dust or other particles carried by the circulated air. A flow meter, such as a venturi, orificemeter, Pitot tube, or the like, may be disposed in the system, if desired, and preferably in the conducting line 42 that serves the altitude chamber 1. An outlet line 47 connects the altitude chamber 1 with the filter 46. The chamber 1 may be of cabinet or of room size, as required for the test to be made therein.

The moisture content of the processed air entering the cabinet 1 is measured in any preferred manner and preferably by dewpoint determinations, since at altitudes up to 35,000 feet, dewpoints of -70° C. to -90° C. have been found to exist. The dewpoint determinations may be made at any desired place in the system, or within the cabinet 1, which position is preferred in the interests of accuracy. As shown on the flow sheet, ambient air entering the predryer 11 normally has a dewpoint within a range of from -15° C. to $+10^{\circ}$ C. depending upon atmospheric conditions. The conducted air leaving the predryer 11 charged with solid carbon dioxide and acetone has a dewpoint within a range between -55° C. to -65° C. The conducted air leaving the calcium sulfate towers 21 has a dewpoint of -78° C. or below, based on atmospheric conditions. When the system is evacuated, the dewpoint is further lowered because of the withdrawal of conducted air

and the resultant expansion of the residual air remaining within the system. The bleeder valve 39 may be partly opened, if desired, to increase the moisture vapor content of the conducted air to a desired value for an accurate reproduction of a desired moisture vapor content within the altitude chamber 1.

The operation of the system is continuous during the period of testing the apparatus. In those situations where the periods of test are brief, 10 more than a single test may be made without changing the exhaustible charges, such as the contents of the refrigerating predryers, the calcium sulfate towers, the precoolers and the filters. Where the periods of test are prolonged, one set of the parallel air conditioning units can be used at a time by the use of the gated arrangement. Additional sets of these units in parallel may be introduced into the air conducting lines for still longer periods of test. The described cycle of operations preferably are gone through for each period of test.

Illustrative problems that are encountered in high altitude flying for the solution of which the present invention is of use include brush wear in moving electrical equipment. It has been found that above 20,000 feet altitude, carbon-copper brush wear is materially accelerated and in some instances with the disintegration of the brushes. Other problems encountered during the operation of radio equipment are the presence of excessive arcing and static electricity and in some cases the complete failure of function in the radio equipment used.

Whereas in some equipment the difficulties encountered in the higher altitudes may be overcome by changes in design and by substitutions of materials or composition, other more complex problems may require repeated and prolonged experimentation before their solution is arrived at. It is with this more complex type of problem that the present invention has proven to be well adapted and reasonably satisfactory.

Activated alumina has been tried experimentally as drying agent in the system that is disclosed herein. If activated alumina is used under pressure, the dewpoint will be lowered upon expansion due to the same amount of moisture being contained in a larger volume. Absorbent cotton has been tried out as a filtering material but has been found to be less desirable in the present installation than activated charcoal which performs the further function of removing organic vapors from the circulated air. The removal of organic vapors is of particular importance involving dynamotor brush wear, since contaminants of this type lubricate the brush commutator contact, accelerate oxidation and their absence increases the wear rate between these moving parts. It is theorized that disintegration of brushes in the stratosphere is due to lack of moisture and impurities in the air of the stratosphere. It is believed that this absence of moisture and impurities prevents oxidation of the contacting surfaces and accelerates the disintegration of the brushes, since the presence of an oxide film between the contacting surfaces of the commutator and the brushes is believed to reduce wear therebetween. Glass wool is preferred as compared with absorbent cotton or similar organic filters because of its absence of absorption and packing, freedom from lint and its

chemically inert characteristics. Infra-red rays may, if desired, be used to obtain very low dew-points in the conducted air.

It is to be understood that the disclosed embodiment of the present invention has been submitted for the purpose of illustrating and describing one preferred form thereof and that various modifications and changes may be made therein without departing from the invention as defined by the appended claims.

What I claim is:

1. In a system of air conditioning, the method of reproducing high altitude physical conditions in a compartment comprising the consecutive flow steps of predrying ambient air by refrigeration, filtering the predried air to remove foreign particles, oil vapors, organic odors, and other contaminants, drying the filtered air, testing the air for the absence of moisture therein, cooling the air, filtering the air, regulating the rate of flow of air, introducing the air into a compartment, and removing the air from the compartment after again filtering the air.
2. In a system of air conditioning, the method of reproducing high altitude physical conditions in a compartment comprising the consecutive flow steps of predrying ambient air by refrigeration, filtering the air to remove foreign particles, oil vapors, organic odors and other contaminants, 25 drying the air, testing the air for the absence of moisture therein, cooling the air, filtering the air, measuring the rate of flow of the air, introducing the air into a compartment, ionizing the air, and removing the air from the compartment.
3. In a system of air conditioning, the method of reproducing high altitude physical conditions in a compartment comprising the consecutive flow steps of predrying ambient air by refrigeration, filtering the air to remove foreign particles, oil vapors, organic odors and other contaminants, 30 drying the air, testing the air for the absence of moisture therein, cooling the air, filtering the air, measuring the rate of flow of the air, introducing the air into a compartment, ionizing the air, and removing the air from the compartment.
4. In a system of air conditioning, the method of reproducing high altitude physical conditions in a compartment comprising the consecutive flow steps of predrying ambient air by refrigeration, filtering the air to remove foreign particles, oil vapors, organic odors and other contaminants, 35 drying the air, testing the air to determine the moisture content thereof, cooling the air, mixing untreated ambient air with said treated air, filtering the air, measuring the rate of flow of the air, introducing the air into a compartment, ionizing the air while in the compartment, and removing the air from the compartment.
